ABSTRACT OF THE DISCLOSURE

The disclosure relates to an apparatus for squaring or otherwise finishing or forming the end or ends of a length of rod, wire, cable or the like. More particularly, it relates to a method and apparatus for squaring the end or ends of a flexible cable to be used as a speedometer cable, in an automatic and continuous, uninterrupted operation.

The method and apparatus of the present invention are particularly applicable for squaring the ends of a flexible shaft to be used as a speedometer cable, in a fashion such as to meet all of the presently existing requirements and/or specifications of the automotive industry. Furthermore, the ends of the flexible shaft are squared in a fashion such that they can be easily and quickly mated with a speedometer head. Further still, the method and apparatus, as will be apparent from the description below, are equally applicable for use in numerous other applications or environments wherein the end or ends of a rod, wire, cable or the like must be squared or otherwise finished or formed.

In the past, several, generally three, individual operations were required to form speedometer cables from a continuous length of flexible cable. For example, the flexible cable first is cut to provide a speedometer cable of the desired length. Normally, this is accomplished on a separate cutting apparatus, and the cut lengths of cable then are transferred to a second station, including a press. At this second station, one end of the cut-to-length flexible cable is inserted into the press, and the latter operated to square that end of the cable. Next, the opposite end of the cable is inserted into the press and likewise squared.

It can be seen that this prior method of forming speedometer cables creates a substantial material handling problem and, furthermore, requires several operators, or else, one operator must perform three separate individual operations, manually. Both require substantial time and labor and, since labor costs are a material consideration, it is apparent that this prior method is costly and therefore undesirable.

Another disadvantage of this prior method is that the squaring on the ends of the cable usually is accomplished by means of V-grooved dies in the presses. It is a generally accepted fact that V-grooved dies result in a cable having diamond-shaped or irregular corners, since it is virtually impossible to apply an equal amount of pressure to the four sides of the cable to form the square. Unless extreme care is taken during this pressing or forming operation, the cable may be unacceptable, since it will not mate properly with the speedometer head.

Accordingly, it is an object of the present invention to provide improved methods and apparatus for squaring or otherwise forming the end or ends of a length of rod, wire, cable or the like.

Another object is to provide improved methods and apparatus for squaring or otherwise forming the ends of a length of rod, wire, cable or the like, in a continuous, uninterrupted operation, all automatically.

A more particular object is to provide improved methods for squaring the end or ends of a flexible cable used

2

as a speedometer cable. In this respect, it is contemplated that the speedometer cable be formed in a continuous, un-interrupted automatic operation.

Still another object is to provide improved methods and apparatus of the above type which are easily and quickly adapted to form any of the standard speedometer cables presently used and which, furthermore, are easily adapted to form virtually any size cable.

Still another object is to provide improved methods and apparatus for forming speedometer cables which have a far faster production rate than presently used methods and apparatus.

A still further object is to provide improved methods and apparatus for forming speedometer cables and the like which are easily and quickly adapted to form them in various lengths.

A still further object is to provide improved methods and apparatus for squaring the end or ends of rods, wires, cables and the like which are adapted to constantly provide substantially perfect cross-sections having square corners, as opposed to diamond-shaped or irregular corners.

Other objects of the invention will in part be obvious and will in part appear hereinafter.

The above objectives are accomplished with apparatus including, generally, a feeding mechanism for feeding a continuous length of rod, wire, cable or the like, hereinafter generally referred to as wire cable, into the apparatus; a forming head including, in the illustrated embodiment, four toggle-actuated forming discs which are simultaneously operated to clamp the wire cable between the peripheral edges thereof and to flatten the sides of the wire cable so as to "square" it; and a wire parter which is operable to sever the material and to fuse the severed ends so as to prevent them from underlaying, at the point along the length of the squared portion thereof. The operation is completely automatic and continuous, once the apparatus is initially set up to form a finished wire cable having a predetermined length.

The invention accordingly comprises the features of construction, combination of elements, and arrangement of parts which will be exemplified in the construction hereinafter set forth, and the scope of the invention will be indicated in the claims.

For a fuller understanding of the nature and objects of the invention, reference should be had to the following detailed description taken in connection with the accompanying drawings in which:

FIG. 1 is a perspective view of a forming apparatus exemplary of the present invention;

FIG. 2 is a side plan view of the forming mechanism of the apparatus of FIG. 1;

FIG. 3 is a sectional view taken generally along lines 3—3 of FIG. 2, illustrating the forming mechanism in its operated position to square the end or ends of the material;

FIG. 4 is a sectional view taken along lines 4—4 of FIG. 2;

FIG. 5 is a side plan view of the cutting head;

FIG. 6 is a side plan view of the forming mechanism, partially sectioned so as to illustrate the manner in which the material to be formed is fed through it;

FIGS. 7 and 8 are side plan views of the forming mechanism, illustrating the manner in which it is operated to clamp the material to square it and to advance the material through the forming mechanism as it is being squared, respectively;

FIG. 9 is a side plan view of one of the forming discs of the forming mechanism;

FIG. 10 is an end plan view of the forming disc of FIG. 9;

FIGS. 11 and 12 are side and end plan views, respectively, of one of the inserts in the forming disc of FIG. 9;

FIG. 13 is a sectional view taken along lines 13—13 of FIG. 2;

FIG. 14 is a perspective view of a portion of the wire cable, illustrating the manner in which it is squared and notched;

FIG. 15 is a sectional view taken along lines 15—15 of FIG. 14; and

FIG. 16 is a plan view of the wire cable, generally illustrating the manner in which it is parted at the notch formed therein.

Similar reference characters refer to similar parts throughout the several views of the drawings.

Referring now to the drawings, in FIG. 1 there is illustrated a forming apparatus 10 exemplary of the invention including a control console 11, a feeding mechanism 12, a forming head 14, a wire parter 15, a sensor unit 16, and a track 17. The control console 11 is of a welded angle construction having sheet material such as 16 gauge aluminum sheet material affixed to it to provide an attractive, protective enclosure for the electrical and pneumatic control circuitry which controls the operation of the forming apparatus. A heavy coat of chip-proof baked enamel preferably is bonded to the sheet material to further enhance its appearance. The control console 11 also has a control panel 18 which is hinged so that it can be opened by pivotally swinging it downwardly, to provide accessibility to the enclosed control circuitry for repairs, if necessary. A number of push buttons, such as the push button 19, a speed control knob 20, and an indicator 21 are mounted on the control panel 18 for controlling the operation of the apparatus 10, in the manner fully described below.

The feeding mechanism 12 is mounted atop the control console 11, and is adapted to feed material which is in the illustrated embodiment is a flexible wire cable 22 (FIG. 6), to the forming head 14. As can be best seen in FIGS. 2 and 13, the feeding mechanism 12 includes frame 24 having a flat mounting plate 25 to which there is affixed a pair of spaced-apart roller support plates 26 and 27. A fixed roller 28 is disposed between the roller support plates 26 and 27 and is affixed to a drive shaft 29. The rotation of the drive shaft 29 is controlled by means of a clutch brake assembly 30 which can be a Warner clutch brake, and has a sprocket 32 affixed to its one end. The sprocket 32 is coupled to and driven by motor means 33 which preferably is a variable speed D.C. motor, by means of a chain drive 34.

A movable roller 36 is affixed to a shaft 37 which is retained within elongated slots 38 formed in the roller support plates 26 and 27 and which is biased downwardly, by means of spring biasing assemblies 39, so as to maintain the roller 36 in peripheral contact with the roller 28.

The rollers 28 and 36 preferably are of nylon or other similar material so as to reduce friction and wearing, and each of them has a semi-circular shaped groove 40 formed in its peripheral edge. These grooves 40 are aligned and preferably are of a dimension such that they form a circular-shaped aperture at the nip thereof which substantially corresponds in diameter to that of the wire cable 22. The wire cable is extended through this aperture and is fed, by the rollers 28 and 36, to the forming head 14.

The forming head 14 includes a frame formed of a toggle arm support member 52 which is fixedly secured to and extends perpendicularly outwardly from a vertically disposed support plate 53. The toggle arm support member 52 has four toggle arm support plates 54 which extend radially outwardly at angles of 90° with respect to one another, and is affixed to the support plate 53 such that the toggle arm support plates 54 are horizontally and vertically disposed. The forming head 14 is mounted atop the control console 11, by means of four pillar supports 41 affixed to the top of the control console and to the horizontally disposed toggle arm supports 54 of the toggle arm support member 52.

The forming head 14 also includes four forming discs 42—45, each of which is affixed to a shaft 46 and is fixedly retained between a pair of generally triangular-shaped clevis arms 70. The shafts 46 and hence the clevis arms 70 and the forming discs 42—45 are each rotatably supported within a pair of toggle arm plates 47 and 48 which together form a toggle arm 50. Four air cylinders 71 are affixed to the support plate 53, and each of the clevis arms 70 is affixed to and operated by a piston rod 72 of one of these air cylinders 71 to rotate its associated one of the forming disc 42—45.

The toggle arms 50 are each pivotally affixed to one of the toggle arm support plates 54 of the toggle arm support member 52, by slidably extending the toggle arm support plates 54 between the toggle arm plates 47 and 48 forming the toggle arms 50 and pivotally securing them therein by means of pivot assemblies 51. The pivot assemblies 51 can be nuts and bolts, as illustrated, or other suitable pivotal fasteners.

The toggle arms 50 also are each pivotally connected to a toggle block 55, by means of a toggle link 62, as can be best seen in FIG. 6. The toggle arm support member 52 is formed to receive the toggle block 55, and to permit the latter to operate in the manner described below. The toggle block 55 has a central bore which is threaded, and a piston rod 56 of an air cylinder 57 is threaded into and preferably through it, as illustrated. The air cylinder 57 is secured to the support plate 53, and the latter has an aperture 58 formed in it, for receiving the piston rod 56. The piston rod 56 has a central bore 59 formed in it, for receiving the wire cable 22 as it is fed to the forming head 14, as can be best seen in FIG. 6. The feed mechanism 12 is fixedly secured to the air cylinder 57, so that the wire cable 22 is fed directly into the bore 59 in the piston rod 56 and the need for additional guide means or the like therefore is eliminated.

The forming discs 42—45 are identical in construction and, as can be seen in FIGS. 9—12 wherein the forming disc 42 is illustrated, the peripheral edges thereof are formed so as to provide two faces 64 and 65 having an included angle of 90° and a flat land 66. This construction allows for positive engagement of all four forming discs 42—45, and thus insures as nearly perfect alignment and pressure distribution on the wire cable 22 as possible to obtain. Each of the forming discs also is adapted to receive three interchangeable segments 67—69, and needle roller bearings (not shown) in its central bore 73. These segments 67—69 are the only portions of the forming discs 42—45 which contact the wire cable 22, and the flat lands 66 thereon each are correspondingly sized to form, respectively, the three standard size wire cables, presently being used in forming speedometer cables. The forming discs 42—45 are merely rotated within the clevis arms 70, to position the appropriate one of the segments 67—69 to engage the wire cable 22. This is accomplished by removing the three screws (not shown), securing the forming disc within the clevis, rotating the forming disc to position the appropriate one of the segments 67—69 in working position, and replacing the three screws. This arrangement therefore provides substantial advantages over the arrangement presently used, since in the latter, a complete die change normally is required.

The automotive industry presently specifies that the squared ends of the speedometer cable also must have a generally rounded or pointed tip on them. This is easily accomplished with the forming apparatus 10, by providing a small, generally triangular-shaped projection 74 on each of the segments 67—69. As the forming discs are rotated, the wire cable 22 is squared, and the projections 74 engage and pinch the wire cable to form a notch 75 in it, as illustrated in FIG. 14. Thereafter, the wire cable is cut at this notch 75 to provide a rounded or generally pointed tip on the ends of two lengths of the wire cable. More particularly, as can be seen in FIGS. 14—16, the length that the wire cable 22 is squared and the position

at which the notch 75 is formed in it is such that, when severed or parted at the notch 75, the length of the squared portion on each end of the severed wire cable corresponds to that which is required on the opposite ends of the speedometer cable which is being formed, in the illustrated embodiment. In other words, the opposite ends of a speedometer cable are formed during two succeeding cycles. The wire cable 22 is squared and notched, and when severed at the notch 75, one speedometer cable is completed and the squared end is provided on one end of the next speedometer cable to be formed. The latter speedometer cable is completed during the next squaring and cutting cycles.

The segments 67-69 preferably and advantageously are skinned when being affixed to the forming discs 42-45, so that a constant radius may be maintained. When the segments are worn and require refinishing, the skin is removed and one corresponding to the amount of material to be removed is placed behind the segment prior to grinding it. Also, as can be best seen in FIG. 9, each of the segments 67-69 is removably affixed to the forming discs by means of two threaded screws 76, so the segments can be easily and quickly replaced or properly skinned for refinishing.

The wire parter 15 is located just forward of the forming head 14 in a predetermined fixed position, as explained more fully below, and, as can be best seen in FIGS. 4 and 5, includes two electrodes 78 and 79, including electrode elements 80, 81 and 82, 83, respectively, which operate in conjunction with one another to sever the wire cable 22. The electrode 78 is stationary, and its electrode elements 81 is fixedly secured to a support base 84 of the wire parter 15. Its electrode element 80, however, is secured to a generally L-shaped pivot lever 85 which is pivotally affixed to a pivot flange 86 secured to the support base 84 and which is pivotally operated by means of an air cylinder 87. The latter is affixed to a vertically disposed arm 89 of the support base 84 and has its piston rod 90 affixed to the pivot lever 85.

The electrode element 83 of the electrode 79 is fixedly secured to a movable base 92 which is slidably supported on the support base 84. An air cylinder 93 is affixed to another arm 94 of the support base 84, and its piston rod 95 is affixed to the movable base 92. Upon operation of the air cylinder 93, the movable base 92 is longitudinally and slidably moved, so as to separate the electrodes 78 and 79. The electrode element 82 is pivotally affixed to the movable base 92 and is pivotally operated by an air cylinder 96, in the same fashion as the electrode element 80.

In operation, the air cylinders 87 and 96 are operated simultaneously to pivotally move the electrode elements 80 and 82 toward the respective electrode elements 81 and 83. The wire cable 22 is clamped between these pairs of electrode elements, and these electrode elements are energized by means of a transformer (not shown) which is, in turn, energized when the electrode elements are in the closed or clamping position to melt the wire cable. The air cylinder 93 also is operated at this time, to move the electrode 79, in spaced relation to the electrode 78. This action causes the wire cable 22 to sever or part, at the notch 75. The movement of the electrode 79 is coordinated so that electrode is moved as the wire cable reaches a molten state, to prevent to some extent spatter and globuling of the molten material. For most efficient operation, the heat generated by the electrodes 78 and 79 should be kept at maximum level. The sealing or fusing of the end of the wire cable 22 is controlled by the speed at which the electrode 79 is moved away from the electrode 78. After parting the wire cable 22, the air cylinders 87, 93 and 96 are de-energized, to release the wire cable and to permit the movable base 92 to return to its initial position.

The sensor unit 16 is mounted on a guide 91 in a fashion such that it can be slidably and lockingly posi-

tioned at any point along the length of the guide 91. The sensor unit 16 includes three high frequency capacitance type sensing heads 97-99 which are mounted in predetermined spaced relationship in a support plate 100, so as to extend over the track 17. These sensing heads 97-99 detect the end of the wire cable 22 as it is advanced in the track 17 and feed control signals to the control circuitry of the forming apparatus 10, to operate the latter in the manner described below.

The track 17 is mounted adjacent to the guide 91 and includes two plates 100 and 101 which are hingedly affixed together in a fashion such as to form a piano hinged V-groove which serves as a wire guide 102. When using a high frequency capacitance type sensor unit 16, as in the illustrated embodiment, the plates 100 and 101 forming the wire guide 102 must be of a material other than steel in order that the wire cable 22 can be detected. The plate 100 of the wire guide 102 has the piston rod (not shown) of an air cylinder 103 affixed to it in a fashion such that the plate 100 is pivotally operated to spill the formed wire cable 22 into a collecting tray 104.

Now that the construction of the forming apparatus 10 has been described, its operation can be described as follows. The end of the continuous length of wire cable 22 is inserted between the nip of the two rollers 28 and 36 of the feeding mechanism 12, and power is then applied to the forming apparatus 10 and the motor 33 of the forming mechanism 12. Next, the clutch brake 30 of the feeding mechanism 12 is energized and released to permit the feeding mechanism 12 to feed the wire cable 22 into the forming apparatus 10. The wire cable 22 is fed between the two rollers 28 and 36, into and through the bore 59 of the piston rod 56 of the air cylinder 57, and between the forming discs 42-45, generally as illustrated in FIG. 6. Initially, at the start of an operation, the wire cable 22 is advanced until its end extends approximately one inch beyond the nip point of the forming discs 42-45. The clutch brake 30 is then de-energized.

The air cylinder 57 next is operated to expel its piston rod 56, to initiate the start of a squaring cycle. The piston rod 56 moves to the left, as illustrated, and in turn, moves the toggle block 55 to the left. This movement of the toggle block 55 simultaneously operates the four toggle links 62, to pivotally move the four toggle arms 50, about the pivot assemblies 51, to clamp the wire cable 22 between the forming discs 42-45, as can be best seen in FIGS. 3 and 7. The pressure exerted on the wire cable 22 by the forming discs 42-45 squares the wire cable at the point of contact. A microswitch controlling a solenoid valve (neither of which are shown) which, in turn, controls the operation of the four air cylinders 71 coupled to the clevis arms 70 is operated by the toggle block 55 when it reaches its forward position. The solenoid valve controlled by it is operated and, in turn, simultaneously operates the four air cylinders 71 to retract their piston rods 72, as illustrated in FIG. 8. As the piston rods 72 are retracted, the clevis arms 70 and hence the forming discs 42-45 affixed to them are rotated in a counter-clockwise direction. The wire cable 22 is advanced between the forming discs 42-45 as the latter rotate, and is squared along a length thereof corresponding to the arcuate angle through which the forming discs 42-45 are rotated. The projections 74 on the working one of the segments 67-69 of the forming discs pinch the wire cable at a predetermined point along the length of its squared portion so as to form the notch 75 in it. When the piston rods 72 of the air cylinders 71 are retracted to form the required squared length on the wire cable 22, another microswitch (not shown) is operated. This microswitch is coupled to and controls the operation of and causes the air cylinders 71 and 57 to restore to their initial operating positions, to ready them for the next cycle of operation.

The wire cable 22 now is moved forward manually, by rotating the upper roller 36 of the feeding mechanism

12 in a clockwise direction, and simultaneously guiding the end of the wire cable through an aperture guide 106 (FIG. 2). The wire cable is advanced until the notch 75 is aligned with the electrode gap 107 of the wire parter 15. When aligned, the air cylinders 87 and 96 of the wire parter 15 are operated to cause the electrode elements 80 and 82 to pivot and to thereby clamp the wire cable between them and the electrode elements 81 and 83, respectively. As indicated above, when these electrode elements 80 and 82 are in the clamping position, the transformer (not shown) which supplies power to the wire parter is energized to heat the wire cable 22 to a molten state and the means (not shown) controlling the operation of the air cylinder 93 is operated to cause the electrode 79 to move away from the electrode 78. The wire cable 22 is thereby caused to part at the notch 75 so that the end of the continuous length of wire cable 22 which is fed through the forming apparatus 10 is squared back along a predetermined length and its tip is generally pointed, as can be best seen in FIGS. 14-16. The remnant cut off the end of the wire cable is removed.

The sensor unit 16 now is slidably positioned along the guide 91 until the centerline of the sensing head 99 thereof is positioned to correspond to the desired length of wire cable. The centerline of the sensing head 99 can be appropriately marked and a calibrated scale provided on the guide 91 or on the wire guide 102 so that the sensor unit 16 can be easily and quickly positioned. The sensor unit 16 is locked in the desired position, by locking means (not shown) such as a toggle clamp or the like.

The forming apparatus 10 now is set up for automatic operation. Upon energizing it, the wire cable 22 will be fed to it by the feeding mechanism 12 and will be rapidly advanced through the forming apparatus 10 to the sensing head 97 which detects it. The sensing head 97 feeds a signal to the control circuit which causes the latter to operate upon the feeding mechanism 12 to slow the rate or speed at which the wire cable is fed to the forming apparatus. This rate or speed can be adjustably controlled by adjusting the speed control knob 20. The end of the wire cable 22 advances at this slower rate to the sensing head 98 which detects it and feeds a signal to the control circuitry to trigger the squaring cycle.

The forming head 14 is operated in the above described fashion to square and to form the notch 75 in the squared portion of the wire cable, and upon completion of the squaring cycle, the wire cable is advanced to and detected by the sensing head 99.

The sensing head 99 feeds a control signal to the control circuitry to trigger the cut-off cycle. The wire parter 15 is operated in the above described fashion to cut the wire cable, and the resulting formed length of wire cable or, in the illustrated embodiment, a speedometer cable of predetermined length, is spilled into the collecting tray 104. The spaced distance between the sensing heads 98 and 99 and between the electrode gap 107 and the centerline of the forming discs 42-45 is equal so that the sensing head 99 triggers the operation of the wire parter 15 when the notch 75 is positioned or aligned with the electrode gap 107. In this way, the operation of the forming head 14 and the wire parter 15 are coordinated so that the wire cable 22 always is severed at the notch 75, during each cycle of operation. This sequence of operation will repeat itself, automatically, until the operation of the forming apparatus 10 is interrupted by turning it "off."

The operation of the forming apparatus 10 to initially set it up for automatic operation and to thereafter automatically form the wire cable is controlled by operating the appropriate ones of the different push buttons 19 on the control panel 19 of the control console 11. An "Emergency Stop" push button also is provided on the control panel 19, the operation of which immediately stops the operation of the forming apparatus 10, in the event of an emergency.

It will thus be seen that the objects set forth above,

among those made apparent from the preceding description, are efficiently attained and, since certain changes may be made in the above construction without departing from the scope of the invention, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention, which, as a matter of language, might be said to fall therebetween.

Now that the invention has been described what is claimed as new and desired to be secured by Letters Patent is:

1. Apparatus for forming a plurality of adjacent, connected flat surfaces on one or both ends of material such as rods, wires, cables and the like comprising, in combination: a forming head including a plurality of forming discs, the peripheral edge of each of said forming discs has two angled faces having an included angle of 90° and a flat land of a predetermined width, said forming discs being positionally disposed and movable with respect to one another to captivate said material between the flat lands on the peripheral edges thereof and to exert pressure on said material so as to flatten said material to provide flat surfaces thereon corresponding in number to the number of forming discs, and means for moving said forming discs to captivate said material between the flat lands on the peripheral edges thereof and to exert pressure on said material to form said flat surfaces.

2. Apparatus, as claimed in claim 1, including four of said forming discs, each of which is disposed and movable with respect to one another so as to provide four flat surfaces on said material, whereby the end of said material has a square cross-section.

3. Apparatus for forming a plurality of adjacent, connected flat surfaces on one or both ends of material such as rods, wires, cables and the like comprising, in combination: a forming head including four forming discs which are positionally disposed and movable with respect to one another to captivate said material between the peripheral edges thereof and to exert pressure on said material so as to flatten said material to provide four flat surfaces whereby said material has a square cross-section, and means for moving said forming discs to captivate said material between the peripheral edges thereof and to exert pressure on said material to form said flat surfaces, said means for moving said forming discs comprising a toggle arm for each of said forming discs, said toggle arms each being affixed at one end thereof to respective ones of said forming discs and at the other end thereof having a toggle link which is affixed to a toggle block, said arrangement being such that said toggle arms are simultaneously pivoted to captivate said material between the peripheral edges of said forming discs when said toggle block is positionably adjusted with respect to said toggle arms.

4. Apparatus, as claimed in claim 3, further including lever means affixed to each of said toggle arms and having the forming disc associated with that toggle arm affixed to it, and means coupled to and pivotally operating said lever means to rotate said forming discs to advance and to square said material along the length thereof which is advanced between said forming discs.

5. Apparatus for forming a plurality of adjacent, connected flat surfaces on one or both ends of material such as rods, wires, cables and the like comprising, in combination: a forming head including four forming discs which are positionally disposed and movable with respect to one another to captivate said material between the peripheral edges thereof and to exert pressure on said material so as to flatten said material to provide four flat surfaces thereon whereby said material has a square cross-section, means for moving said forming discs to captivate said material between the peripheral edges

thereof and to exert pressure on said material to form said flat surfaces, feeder means for feeding said material to said apparatus, cutting means for severing said material, sensor means for detecting the end of said material, and control means operated in response to control signals from said forming head and said sensor means to operate said feeder means to feed said material to said apparatus, to operate said forming head to square said material, to operate said sensor means to measure a predetermined length of said material, and to operate said cutter means to sever said measured length of material, automatically and in a repetitive fashion.

6. Apparatus, as claimed in claim 5, wherein said feeder means comprises a pair of rollers adapted to retain said material between them in a fashion such that said material is advanced when said rollers are rotated, at least one of said rollers being rotatably driven, and clutch brake means coupled to said rotatably driven roller for controlling its rotation.

7. Apparatus, as claimed in claim 5, wherein said cutting head comprises a fixed electrode and a movable electrode, each having a fixed electrode element and a movable electrode element which is pivotally operable to clamp said material between it and said fixed electrode element, said fixed and movable electrodes being energized when said movable electrode elements have pivotally operated to clamp said material to heat said material sufficiently so that said material will sever when said movable electrode is moved away from said fixed electrode.

8. Apparatus, as claimed in claim 7, wherein said cutting head includes an air cylinder coupled to each of said movable electrode elements which are simultaneously operable to pivotally operate said movable electrode elements to clamp said material between them and said fixed electrode elements and an air cylinder coupled to and operable in timed relationship with the operation of said movable electrode elements to move said movable electrode away from said fixed electrode.

9. Apparatus, as claimed in claim 5, wherein said sensor means comprises three high frequency capacitance sensing heads affixed to support means in spaced relationship to one another, a first one of said sensing heads being operable to detect the end of said material and to feed a control signal to said control means to cause said feeder means to slow the rate of feed of material to said apparatus, a second one of said sensing heads being operable to detect the end of said material and to feed a control signal to said control means to cause said forming head to operate to square said material, and a third one of said sensing heads being operable to detect the end of said material and to feed a control signal to said control means to cause said cutting means to operate to sever said material.

10. Apparatus, as claimed in claim 5, further including

a guide for slidably supporting said sensor means to permit said sensor means to be positionably located with respect to said cutting head to cut a length of material having a predetermined length, a collecting tray, and a V-shaped track adjacently affixed to said guide for supporting said material as it is advanced, said track having one side thereof which is pivotally operable to spill the cut length of material into said collecting tray.

11. Apparatus, as claimed in claim 1, wherein each of said forming discs has a projection on said flat land, said projections being adapted to pinch said material to form a notch in it.

12. Apparatus, as claimed in claim 1, wherein each of said forming discs has a plurality of insert segments removably affixed to it, each of said insert segments having the peripheral edge formed with two angled faces having an included angle of 90° and a flat land of a predetermined width sized in accordance with the material upon which the flat surfaces are to be formed, said flat lands on each of said segments being different, whereby said flat surfaces can be formed on different diameter materials simply by rotatably adjusting said forming discs to place the appropriate one of said insert segments in a working position.

13. Apparatus, as claimed in claim 12, wherein each of said insert segments has a projection on its flat land, said projections on the working ones of said insert segments being adapted to pinch said material to form a notch in it.

14. Apparatus, as claimed in claim 11, wherein said cutting means is mounted in a spaced position from the centerline of said forming discs and wherein said sensor means has at least two sensing heads operable to detect the end of said material and to feed a control signal to said control apparatus to cause said forming head to operate to square said material and to cause said cutting means to operate to sever said material, respectively, said two sensing heads being spaced apart a distance corresponding to the distance between said cutting means and the centerline of said forming discs, whereby said cutting means is operated to sever said material at said notch so as to simultaneously provide an end having a squared cross-section and a generally pointed tip on the opposite ends of two lengths of said material.
